UNITED STATES PATENT OFFICE.

VICTOR THOMAS HUNTER, OF BRADFORD, ONTARIO, CANADA.

COLLAPSIBLE BOX OR CRATE.

Application filed April 8, 1924. Serial No. 704,908.

To all whom it may concern:

Be it known that I, VICTOR THOMAS HUNTER, mechanic, a subject of the King of Great Britain, residing in Bradford, in the county of Simcoe, Province of Ontario, Canada, have invented certain new and useful Improvements in Collapsible Boxes or Crates, of which the following is a specification.

10 My invention relates to improvements in collapsible boxes or crates, adapted to be used in shipping merchandise, or poultry, and the object of the invention is to provide an economical and simple construction which will provide the necessary strength and rigidity when set up for use, and which may be readily knocked down or collapsed to occupy small space for re-shipment or storage.

20 Fig. 1 is a perspective view of my box or crate as it appears when in use. Fig. 2 is a side elevation of the box or crate partly opened, and Fig. 3 is a plan view thereof when partly folded. Fig. 4 is a side elevation of the box or crate completely folded.

In the drawings, like characters of reference refer to the same parts.

The structure embraces bottom and top frames A and B and end frames C and D. 30 These frames each embrace a pair of longitudinal members 2, coupled together by any suitable means. In the preferred construction the said frames are of open work, though they may be closed. The members 2 of the frames B, C and D are tied together by the cross pieces 3 and 4, and are provided with slats 5 diagonally disposed to form braces. The lower ends of the longitudinal members 2 of the end frames C and 40 D overlap the sides of the longitudinal members 2 of the top and bottom frames B and A, and therefore the end frame C is wider than the bottom frame A, and the end frame D wider than the top frame B.

45 The cross pieces and slats connecting the longitudinal members 2 of the end frames C and D are connected to the narrower sides of said longitudinal members, and project beyond said narrower sides, and this is for the purpose of permitting the top frame B to be housed within the end frame D, and the end frame C to fold snugly over the bottom frame A.

55 The upper ends of the longitudinal members 2 of the frames C and D overlap the longitudinal members 2 of the upper frame

B, and passing through the upper ends of the longitudinal members 2 of the frames C and D and the adjacent outer ends of the members 2 of the upper frame B are tie rods 6 and 7 respectively. The tie rod 6 is adapted to be removed to permit the structure to be opened or collapsed, whereas the tie rod 7 is adapted to be permanently held in place and to act as a hinge. Also passing through the lower ends of the members 2 of the frame C, and through the adjacent outer ends of the members 2 of the frame A is a tie rod 8, which is adapted to be permanently located, and to act as a hinge.

The end frame D is coupled by hinges 10 through the medium of its cross piece 3 to the bottom frame A through the medium of the cross piece 11 thereof.

12 and 13 are diagonal braces located in pairs at each side of the structure. The lower ends of the braces 12 are mounted on the tie rod 8 near the outer ends thereof, and the lower ends of the braces 13 are mounted on the bolts 9 which bolts are held in the lower ends of the members 2 of the end frame D. Also mounted on the ends of the tie rod 8 and beyond each side of the members 2 of the frame C are spacing devices 14, preferably in the form of rubber rings. 85 These spacing devices are substantially of the same thickness as the braces 13 so that when the structure is collapsed fully as shown in Fig. 4, the braces 13 will move into the desired position.

The upper end of each brace 12 is slotted as shown at 15 so as to permit these braces to be detachably coupled to the tie rod 7 at each end thereof when the structure is set up. The tie rod 6 passes through the outer ends of the braces 13 when the structure is set up.

The braces 12 are longitudinally slotted as shown at 16, and through these slots extend rivets or bolts 17 held in the braces 13. 100 As the structure is opened by first removing the tie rod 6, the braces 12 may be disengaged from the tie rod 7 by manipulating the braces 13. These braces 12 may also be raised into position by reason of the co-action therewith of the braces 13, when it is desired to set the structure up.

The upper frame B is adapted to fold within the end frame D, and the end frame C is adapted to fold over the bottom frame A (see Fig. 3). The frames B and D are then moved on the hinges 10 to be placed

underneath the bottom frame A (see Fig. 4), when the structure is completely collapsed. The diagonal braces 12 and 13 are of course moved into the position shown in Fig. 4 and then the tie rod 6 is passed through holes *a* formed in the braces 12 near the outer ends thereof.

Since it forms no part of this invention, the nut or other removable retaining means 10 on the tie rod 6 is not shown, since it must be understood that some such element must be used with said tie rod. The longitudinal members 2 of the bottom frame A are also coupled together adjacent the tie rod 8 by cross piece *b*, and said longitudinal members are suitably braced as shown at *c*.

What I claim is:

1. A structure of the class described comprising a bottom frame; a first end frame 20 hinged at its lower end to one end of said bottom frame to straddle same; a second end frame hinged to the other end of said bottom frame to straddle same, and adapted to fold over said bottom frame; a top frame hinged at one end to the upper end of said first-mentioned end frame and within the same; a first brace at each side of said structure each hinged at its lower end to the hinging means for said second-mentioned end frame, each brace adapted to be 30 removably coupled to the hinging means coupling said top frame to said first-mentioned end frame; a second brace located at each side of said structure; means pivoting the lower end of each of said second-mentioned braces to the lower end of said first-mentioned end frame; means carried by said second-mentioned braces and adapted to operate in the slot formed in each of said longitudinally slotted braces, and a coupling device passing through the upper end of each of the said second-mentioned braces and through the overlapping ends of said second-mentioned end frame and said top frame.

2. A structure of the class described com-

prising a bottom frame; a first end frame hinged at its lower end to one end of said bottom frame to straddle same; a second end frame hinged to the other end of said bottom frame to straddle same, and adapted to fold over said bottom frame; a top frame hinged at one end to the upper end of said first-mentioned end frame and within the same; a longitudinally slotted brace at each side of said structure each hinged at its lower end to the hinging means for said second-mentioned end frame, each brace adapted to be removably coupled to the hinging means coupling said top frame to said first-mentioned end frame; another brace located at each side of said structure; means pivoting the lower end of each of said second-mentioned braces to the lower end of said first-mentioned end frame; means carried by said second-mentioned braces and adapted to operate in the slot formed in each of said longitudinally slotted braces, and a coupling device passing through the upper end of each of the said second-mentioned braces and through the overlapping ends of said second-mentioned end frame and said top frame.

3. A structure of the class described comprising a bottom frame; a first end frame hinged at one end to one end of said frame and adapted to fold over the same; a second end frame hinged at one end to the other end of said bottom frame and adapted to be folded thereunder; a top frame hinged at one end to the upper end of said second-mentioned end frame and adapted to fold within said second-mentioned end frame; diagonally disposed braces located in pairs at each side of said structure and co-operatively associated therewith to give rigidity to said structure when set up, and means coupling the upper end of said first-mentioned end frame to the associated end 80 of said top frame, and binding certain of said diagonal braces in place.

VICTOR THOMAS HUNTER.
